UNITED STATES PATENT OFFICE.

BENJAMIN WENDER AND JAMES BRUNELLI, OF NEW YORK, N. Y.

IRONING-PAD.

1,134,430.

Specification of Letters Patent.

Patented Apr. 6, 1915.

Application filed February 1, 1915. Serial No. 5,345.

To all whom it may concern:

Be it known that we, BENJAMIN WENDER and JAMES BRUNELLI, respectively a citizen of the United States and a subject of the 5 King of Italy, and residing at New York, in the county of New York and State of New York, have invented certain new and useful Improvements in Ironing-Pads, of which the following is a specification, such 10 as will enable those skilled in the art to which it appertains to make and use the same.

This invention relates to pads for use in ironing or pressing cloth of various kinds 15 and classes, such as woolen cloth, velvet, duvetines and the like, either in the piece, or made up into garments of various kinds and classes, and especially in pressing or ironing garments made of the material referred to when it is desired to re-press, 20 sponge and press or iron said garments; and the object of the invention is to provide an improved pad of the class and for the purpose specified, whereby the cloth or garment 25 when so treated will be given a fresh and new look or appearance, and resemble new cloth or a new garment, and with this and other objects in view the invention consists in a pad of the class and for the purpose 30 specified, constructed as hereinafter described and claimed.

The invention is fully disclosed in the following specification, of which the accompanying drawing forms a part, in which the 35 separate parts of our improvement are designated by suitable reference characters in each of the views, and in which:—

Figure 1 is a front view of our improved ironing pad; Fig. 2 a side view thereof; 40 Fig. 3 a back view of a portion of the pad on an enlarged scale; and, Fig. 4 a section on the line 4—4 of Fig. 3.

In the practice of our invention, we provide a pad *a*, comprising a body portion *a*² 45 composed of wire mesh or woven from wire of any suitable class.

In the form of construction shown the body portion *a*² is composed of two sets of wires *a*³ and *a*⁴ which run longitudinally 50 therethrough and two other sets of wires *a*⁵ and *a*⁶ which cross the wires *a*³ and *a*⁴ at right angles thereto and in the weaving of said body portion, the wires *a*⁶ catch and draw into said body portion another wire 55 or wires from which loops *b* are formed, said other wire or wires being cut off to

form said loops, and these loops *b* form a mat or brush *b*² on the front of the body of the pad, consisting of fine wires which project in the manner of the bristles of a brush. 60 The mat or brush *b*² is preferably of less dimensions than the back or body of the pad, and it will be understood that the said pad may be made of any desired length and width or of any transverse and longitudinal dimensions. 65

In the use of a pad of this class, in the operation of ironing or pressing cloth or garments, the pad is placed on the cloth or garment with the brush material or teeth 70 projecting downwardly and into said cloth or garment or the nap thereof, after which a moistened cloth is placed on the back of the pad and the iron is passed thereover in the usual manner, and in this operation the 75 brush *b*², or the material thereof which penetrates the nap of the cloth or garment and also enters the body portion thereof opens up said nap and body portion and the vapor or steam formed by the iron in contact with 80 and passing over the ironing cloth, passes through the pad and into the cloth or garment that is being ironed or pressed and permeates the nap and the body of said cloth or garment and the effect of this is 85 to give said cloth or garment a fresh and new appearance.

By making the back or body of the pad of wire mesh, or weaving said back or body of wire, the said back or body is provided 90 with numerous small apertures or passages through which vapor, steam or hot air is free to pass and this facilitates and renders practical the use of the pad as hereinbefore described. 95

We are aware that pads for a purpose similar to ours have heretofore been made, but the backs or bodies of these pads were woven so tight that steam, vapor or air could not pass therethrough, and the said back or body portions had to be perforated to permit of this operation, but with our improvement the back or body portion of the pad being composed of wire mesh, or woven from wire material is sufficiently open in its construction or formation to permit of the free passage of steam, vapor or air, and with our improvement the brush material *b* which forms the brush *b*² is woven into the back or body of the pad and the 105 formation of the entire pad involves but one 110 operation.

It will be understood that the back or body portion of the pad may be made of any desired thickness and, if desired, another thickness of wire mesh may be secured to that into which the brush material is woven in order to provide any desired thickness for the back or body portion.

Having fully described our invention, what we claim as new and desire to secure

10 by Letters Patent, is:—

1. An ironing pad, comprising a body portion composed of wire mesh and one side of which is provided with projecting brush material also composed of wire.

15 2. An ironing pad, comprising a body

portion composed of wire mesh and one side of which is provided with projecting brush material also composed of wire and consisting of loops which are woven into the body of said mat.

20 In testimony that we claim the foregoing as our invention we have signed our names in presence of the subscribing witnesses this 28th day of January, 1915.

BENJAMIN WENDER.
JAMES BRUNELLI.
